Primary Examiner — Catheri Oliver-Garcia(74) Attorney, Agent, or Firm — Gulf Coast Intellectual Property Group(57) CLAIM

The ornamental design for a medicine holder and organizer, as shown and described.

DESCRIPTION

FIG. 1 is a perspective view of the present invention in an open position wherein one of the pill containers is removed from the pill container grid; and

FIG. 2 is a perspective view of the present invention in an open position with the pill container grid removed from the interior thereof; and

FIG. 3 is a front view of the present invention in an open position; and

FIG. 4 is a rear view of the present invention in an open position; and

FIG. 5 is a left side view of the present invention in an open position; and,

FIG. 6 is a right side view of the present invention in an open position.

The broken lines shown in the drawings depict environment and illustrate use and form no part of the claimed design.
